MAYHEW E. NOYES, OF CLEVELAND, OHIO.

NUT-TAPPING MACHINE.

1,218,691.

Specification of Letters Patent. Patented Mar. 13, 1917.

Application filed August 30, 1913. Serial No. 787,414.

To all whom it may concern:

Be it known that I, MAYHEW E. NOYES, a citizen of the United States, residing at Cleveland, county of Cuyahoga, State of Ohio, have invented a certain new and useful Improvement in Nut-Tapping Machines, and declare the following to be a full, clear, and exact description of the same, such as will enable others skilled in the art to which it pertains to make and use the same, reference being had to the accompanying drawings, which form a part of this specification.

This invention relates to machines for tapping nut blanks or the like, and its object is a comparatively simple and efficient machine for automatically threading apertured blanks which are continuously fed to the tap and automatically removed therefrom. A novel feature of the invention resides in the mechanism employed in feeding the blanks onto the tap and in holding the tap and revolving the blank relative thereto to thread the same, and also in the mechanism employed in holding the tap and the arrangement whereby the finished blanks are removed from the tap in succession. These and other objects and novelties of the invention are hereinafter more fully described and claimed and shown in the accompanying drawings in which—

Figure 1 is a vertical section of my improved device on line $\alpha-\alpha$ of Fig. 2.

Fig. 2 is a front elevation of the device partly in section taken on line $\alpha-\alpha$ of Fig. 1.

Fig. 3 is an enlarged detail partly in section showing the collet or chuck for the blanks in its relation to the tap and the means of operating the same.

Fig. 4 is a detail plan view of the tap holding device.

Fig. 5 is a detail of means employed to reciprocate the push-bar to remove a blank from the hopper to the chuck or collet.

Fig. 6 is a plan view of the blank holding hopper and the race-way at the bottom thereof leading to the open end of the chuck.

Fig. 7 is a detail in perspective of the interior of one side of the chuck.

Similar characters refer to similar parts throughout the drawings and specifications.

The device consists of a framework 1 having a feed table 2 and a delivery table 3. The upper portion of the framework is arranged to support the drive shaft and other

mechanism hereinafter described. The machine, as may be inferred from Fig. 2, is provided with duplicate tapping devices to each of which blanks are automatically fed from hoppers individual thereto as herein-after shown, and a description of one of these devices is believed sufficient for all, and as each is actuated and operates in the same manner and, while only two of such devices are shown in the drawing, the machine may be designed to include and to jointly operate as many such devices as may be practicable.

At the rear of the feed table and substantially centrally of the machine is the chuck 4, the upper end of which is practically flush with the upper surface of the feed table. Also mounted on the feed table is a hopper 5 for the blanks which is open at both ends and a push-bar 6, hereinafter described, reciprocates beneath the open lower end of the hopper removing a blank therefrom and forcing it out over the upper open end of the chuck where it is held between the spring pressed fingers 7 and 8.

In vertical alinement with each chuck is a plunger 9 having a removable lower end portion 10 the end of which engages the blank placed between the fingers 7 and 8 forcing it downward into the chuck. The chuck, being revolved in a manner herein-after described, revolves the blank and threads it onto the tap 50 which is held from rotation centrally within the chuck. The end of the said portion 10 is hollow in order that the end of the tap may pass therewith as the plunger end forces the blank onto the tap.

The main drive-shaft 11 extends across the machine at the rear of the said chucks and, at a point opposite each chuck, a spiral drive gear 12 is keyed to the shaft 11, meshing with a corresponding spiral gear 13 on the chuck retainer 14. The chuck and related parts are shown more clearly in Fig. 3, and it may there be seen that the holder 14 is carried in the frame on ball bearings 15 to reduce the friction produced by the forcing of the blank into the tap. The chuck 4 is set into the holder 14 which is slotted at 16, 16, to receive the ears 17 on the chuck. The upper end of the holder is threaded to receive the securing nut 18 which engages the ears on the chuck, holding it in position in the holder and also holding it from rotation relative to the

holder whereby rotation of the holder through the medium of the gears rotates the chuck about the tap. The chuck is preferably made in two halves and is removable from the holder by removing the nut 18 whereby chucks of various sizes may be used with the machine, which is thus adapted to operate on blanks of various sizes. The end portion 10 of the plunger 9, being in threaded engagement with the plunger may also be readily removed and replaced by a similar part of greater or less size depending upon the size of tap and chuck employed.

As may be seen more clearly in Fig. 1, 15 the plunger 9 is provided with a collar 19 fixed thereto and a collar 20 below the collar 19 slidable on the plunger carried in the forked end 21 of the cam lever 22 pivoted at 23 to the upper part of the framework. 20 The lever 22 is provided with a roller 24 extending to one side thereof as may be seen in Fig. 2 engaging in a cam groove 25 in a cam wheel 26 on the shaft 27, which shaft is driven by sprocket chain 28 from the main 25 drive shaft 11.

By reason of the roller 20 being slidable on the plunger 9, it engages the collar 19 and raises the plunger during rotation of cam wheel 26 at which period a blank is introduced between the fingers 7 and 8 over the upper end of the chuck. The collar 20 thereupon descends relative to the plunger allowing the plunger to rest on the blank whereby the weight only of the plunger 30 forces the blank downward into the chuck and on to the tap which arrangement allows the blank to feed onto the tap, as is determined by the revolution of the chuck. The weight of the plunger thus insures the positioning of the blank and starting it onto the tap. The blank is then drawn downward onto the tap 50, which is held stationary, at a speed which is determined by the pitch of the threads on the tap.

45 As is shown more clearly in Fig. 3, the upper end of the chuck is counter-bored a distance approximately equal to the thickness of the nut blank to be used therewith, the diameter of the counter-bore being 50 slightly greater than the distance across corners of the blank, and the chuck is beveled from one corner to the next at the bottom of the counter-bore on each hexagonal face of the chuck, as shown at 29, to insure the 55 blank passing down into the chuck a sufficient distance to be caught and revolved thereby. By this construction of the chuck, the nut blank may be forced into the receiving end thereof a certain distance before being rotated thereby. As the chuck rotates, it happens more often than otherwise that the hexagonal faces of the nut blank, on being delivered into the counterbore, do not register with the faces of the chuck but, by 60 providing the counterbore in the chuck some-

what greater in diameter than the distance across corners of the blank, the blank may readily enter the throat and, if the faces are not in registration with the faces of the chuck, the corners of the blank rest on the inclined or beveled edges 29. As the plunger operates to force these blanks downward into the chuck and onto the tap during rotation of the chuck, the corners of the nut blank supported on the inclined edges 29, 70 ride off therefrom which turns the blank until the faces thereof register with the corresponding faces of the chuck. The tap terminates slightly below the bottom of the counterbore so the blank is properly set in 75 the chuck prior to engaging the tap.

As shown more fully in Figs. 2 and 6, the hopper for the blanks is formed of two oppositely positioned plates 30 and 31 provided with slots in which the studs 32 are positioned whereby the plates 30 and 31 may be moved forward or back to adjust the hopper to receive blanks of various sizes. Each plate is provided with an upright portion 33, secured to which are plates 34 of such form 90 as to engage about the hexagonal blanks. As shown more clearly in Fig. 6, to each plate 30 and 31 is hingedly secured a finger 7 and 8 respectively forming with the plates a raceway at the bottom of the hopper 95 formed by the portions 33 and plates 34. Each finger 7 and 8 is provided with a laterally extending portion 35 to which is secured a leaf-spring 36 engaging against the plate 30 or 31 to which the finger is hinged. 100 These springs tend to force the free ends of the fingers together and, therefore, a nut blank forced out between the fingers is held in position by reason of the springs engaging against the plates. 105

As heretofore stated, the blanks are removed from the hopper by means of a push-bar 6, there being a bar 6 for each hopper on the machine, which is adjustably mounted on a slide 37 more clearly shown in Figs. 1 110 and 2. This slide is reciprocated by a gear 38 on the shaft 39 which has an oscillatory movement produced by mechanism more clearly shown in Figs. 2 and 5. The shaft 39 is provided with a gear 40 near one end 115 thereof carried in a casing 41, in the upper portion of which is a rack 42 connected by a link 43 to the end of a lever 44 pivoted at 45 to the frame of the machine. The outward end of the lever 44 is provided with a roller 46 engaging in a cam groove 47 which may be conveniently formed upon one side of one of the cam wheels 26, and the cam 47 is so formed as to move the rack 42 backward and forward across the face of the gear 40 thereby oscillating the shaft 39, and through the medium of the gears 38 reciprocating the slides 37. The gears 38 are not keyed to the shaft 39 but each is frictionally held from rotation by the fiber disks 380 and 120 125

381 which are drawn tightly into engagement with the sides of the gear by the nut 382 on the collar 383 pinned to the shaft. The fiber disks are clamped between the 5 head of the collar and the nut. This arrangement allows the gears to slip and prevents injury thereto if a blank should be caught or held in any unintended manner.

As may be seen more clearly in Fig. 1, the 10 push-bar 6 is slotted to receive a set screw 48, and the slide 37 is provided with a set screw 49 engaging the end of the push-bar so that the push-bar may be set in any desired position with the end thereof engaging 15 against the screw 49 and secured in position by the set screw 48. The push-bar may thus be adjusted to accommodate different sizes of blanks, and as the push-bar is brought forward beneath the hopper the blank is 20 pushed out between the spring pressed fingers 7 and 8 and positioned above the chuck into which it is forced by the weight of the plunger which is brought to rest thereon at the properly timed intervals, as determined 25 by the cam 25.

As may be seen more clearly in Figs. 1 and 3, the tap 50 is provided with a shank 51 less in diameter than the tap onto which the finished blanks pass as they thread themselves 30 off from the tap. The tap is held from rotation by two pairs of pivoted arms 52, 52^a and 53, 53^a, each carrying a jaw 54 of V shaped face adjustable in a socket in the end of each of the arms by means of the set 35 screws 55 and 56, shown more clearly in Fig. 4. The opposite ends of the arms are provided with like extensions 57 upon which are positioned rollers 58, 58, and at the extreme end a coiled spring 59 is secured, there 40 being a spring 59 for each pair of arms which tends to hold the jaws in an open position.

As may be seen in Fig. 1, these jaws are pivoted on a rod 60 and a cam rod 61 is provided at the rear thereof vertically reciprocatable in bearings provided in the framework. This rod is provided with a cut-out or cam portion 62 and when cam portion 62 is brought between the rollers 58 of one pair 50 of arms, the spring 59 draws the rollers into contact with such narrow portion of the rod 61 and opens the jaws which are closed when the full diameter of the rod is forced between the rollers. The narrow cam portion 55 of the rod is of such length that only one pair of the arms are allowed to open at a time, and thus, in a vertical movement of the rod 61 in its bearings, the lowermost pair of arms may first open and as the portion 62 of the rod passes from between the rollers on the arms the lower jaws close, there being a slight interval of time in which both sets of jaws are closed, and as the part 60 62 travels upward, the upper jaws on the 65 arms 52 open. The blank in traveling down

the shank 51 of the tap first rests upon the jaws of the upper arms 52 and when they are opened by a proper movement of the cam rod this blank falls by gravity onto the jaws in the lower arms 53 which are at that 70 time closed. The cam rod 61 then descends closing the upper jaws, which will stop the succeeding blank from the tap, and then opens the lower jaws which will allow the first blank to pass off from the end of the 75 shank onto the delivery table 3, and thence to the floor or receptacle positioned to receive the blanks.

It is thus to be seen that the tap is continuously held, one or the other of the sets 80 of jaws being clamped onto the shank of the tap. The shank is made square in cross-section, as may be seen in Figs. 3 and 4, at those points engaged by the V shaped jaws 85 54 in both sets of arms and the jaws being V shaped rotation of the shank and tap is prevented. The distance across corners of the squared portions of the shank is not greater than the diameter of the shank and, therefore, the finished nuts may pass freely 90 by gravity down the shank.

The vertically positioned cam rod 61 is reciprocated in its bearings by a lever 63 pivoted to the frame, one end of which is slotted to receive the rod 61, and to the opposite end is pivoted a rod 64. To the end of the lever 22 is pivoted a similar rod 65, and contiguous ends of the rods 64 and 65 are threaded to receive the right and left hand threaded ends respectively of the adjusting 95 screw 66. This adjusting screw enables the cam rod 61 to be properly positioned relative to the holding arms 52 and 53, and rotation of the cam wheel 26, which operates the lever 22 through the medium of the roller 24 in 100 the cam groove 25, reciprocates the cam-rod 61 in its bearings. As shown in Fig. 1, the lower part of the machine is provided with a chamber 70 and the delivery table 3 does not extend completely over the chamber thus 105 providing an opening 71 into said chamber at the lower end of the delivery table. This chamber is partially filled with oil and a centrifugal pump 72 is located at the back of the machine provided with an inlet in 110 communication with this oil chamber 70, and as shown by dotted lines in said Fig. 1, a flexible tube 73 is provided extending from the outlet to the pump to the hollow interior of the end portion 10 of the plunger, whereby oil is continually fed onto the nut blank and tap during operation of the machine. The oil flowing onto the blank passes through the chuck and falls onto the delivery table 3 down which it flows by gravity 115 and into the chamber 70 through the opening 71 heretofore mentioned. The slot or opening 71 is so positioned that finished nuts in passing down the delivery table pass over the opening 71 and do not fall into the cham- 120 125 130

ber. The inlet to the pump, as is usual in a device of this nature, is provided with a screen to prevent metallic waste passing into the pump.

5 In operation each hopper 5 is filled with blanks and is kept in such condition by any approved means, or by an attendant, and these blanks are fed one by one to and between the spring pressed fingers 7 and 8 10 above each chuck or collet 4. The end 10 of each plunger is then brought to rest upon these blanks, the weight of which forces the blank from between the fingers into the rotating chuck which rotates the blank by reason of its being engaged by the hexagonal 15 faces and inclined upper edges 29 thereof at the bottom of the counter-bore in the chuck. As these blanks rotate they are forced downward onto the taps 50 down which they move 20 by reason of the pitch of threads on the taps. The cams operating the plungers are of such shape as to allow the plungers to rest on the blanks for a period sufficient to insure their being engaged by the taps whereupon the 25 plungers are raised, a blank inserted between the fingers 7 and 8 and the operation repeated. The first blank continues its travel down the tap while a second blank is being positioned in the upper end of the chuck. 30 As the finished nut passes from the tap, it falls by gravity down the shank thereof on to the upper pair of jaws which hold the shank, as shown by dotted lines in Fig. 3. The upper jaws then open allowing the 35 blank to fall onto the lower holding jaws as shown by full lines in Fig. 3. The upper jaws then close engaging the shank, and the lower jaws then open allowing the blank to drop off the end of the shank onto the delivery table.

It is thus to be seen that the operation of the machine is entirely automatic, it only being necessary to keep the hoppers filled with the apertured blanks, which are continuously fed into the machine and pass therefrom in a finished condition.

Having thus fully described my invention, its utility and mode of operation, what I claim and desire to secure by Letters Patent 50 of the United States is—

1. In a nut tapping machine, a continuously rotatable chuck, a tap therein, means for supporting a stack of blanks adjacent the chuck, a blank holding device above the 55 chuck, means for transferring a blank from the stack to the holder, and means for delivering the blank from the holder into the chuck and onto the tap.

2. In a nut tapping machine, a continuously rotatable chuck, a tap held stationary within the chuck, means for supporting a stack of blanks adjacent the chuck, a holder for a single blank adjacent the mouth of the chuck, means for transferring a blank 65 from the stack to the holder, and a plunger

for transferring the blank from the holder into the chuck and onto the tap.

3. In a nut tapping machine, a continuously rotatable chuck, a stationary tap extending into the chuck, a blank holding device adjacent the mouth of the chuck, means for delivering blanks in succession to the holding device, means for transferring a blank from the holding device into the chuck, the chuck being recessed to receive the blank prior to its engagement with the tap, and means for delivering the finished nuts from the tap.

4. In a nut tapping machine a continuously rotatable chuck, a stationary tap extending into the chuck, means for introducing blanks in succession into the chuck, the chuck being recessed to receive the blank prior to the engagement thereof with the tap, and means for delivering the finished nuts from the tap.

5. In a nut tapping machine, a continuously rotatable chuck, a stationary tap extending into the chuck, means for introducing blanks in succession into the chuck, said means including a plunger for forcing the blank into the chuck, the chuck having faces corresponding with the faces of the blank for a portion of its length, said chuck being recessed at the mouth to receive the blank prior to its engagement with the tap and so formed that movement of the blank longitudinally of the chuck turns the blank to bring the faces into registration with the faces of the chuck prior to engagement of the blank with the tap, and means for delivering the finished nuts from the tap.

6. In a machine of the kind described, a hollow rotatable chuck for blanks, a tap within the chuck, automatic mechanism for positioning blanks consecutively in the chuck in engagement with the tap, the receiving end of the chuck being counter-bored a depth substantially equal to the thickness of the blank and of a diameter greater than the distance across corners of the blank, said chuck having faces corresponding to the side faces of the blank, said faces on the chuck being beveled or inclined at the bottom of the counter-bore to insure proper engagement of the blank thereby, and means for holding the tap stationary, said means being arranged to pass the finished blanks consecutively from the tap.

7. In a machine of the kind described, a vertically positioned hollow chuck for blanks, means for continuously rotating the chuck, a vertically positioned tap within the chuck provided with a shank extending from the delivery end of the chuck, a hopper for blanks, intermittently actuated means for removing a blank from the hopper, means for receiving and holding the removed blank above the receiving end of the chuck, a gravity actuated plunger for forcing the blank

- into the chuck in engagement with the tap, means for raising the plunger for successive operations, the rotation of the chuck forcing the blank downward longitudinally of the 5 tap, and means engaging the said shank of the tap for holding the tap stationarily with the chuck, said shank being less in diameter than the threaded aperture in the blank whereby the finished blanks may pass by 10 gravity down the shank, said holding means for the tap being arranged to allow the finished nuts to pass by gravity off from the tap.
8. In a machine of the kind described, a 15 hollow chuck for nut blanks, means for continuously rotating the chuck, a stationary tap within the chuck, a hopper for blanks, blank receiving means adjacent the receiving end of the chuck, a reciprocatable push-bar, 20 for consecutively removing blanks from the hopper and delivering them to the said blank receiving means, means for reciprocating said push-bar, a gravity actuated plunger for forcing a blank from the said receiving 25 means into the chuck in engagement with the tap, the rotation of the chuck forcing the blank longitudinally of the tap, and means for raising the plunger for successive operations.
- 30 9. In a nut tapping machine, a hollow rotatable chuck for blanks having a number of interior faces corresponding to the number of sides of the blank formed parallel with the axis of the chuck and extending a 35 portion of the length thereof, the mouth of the chuck being counterbored and adapted to receive a blank, the ends of the faces adjacent the counterbore being formed at an angle to the longitudinal axis of the chuck, a 40 stationary tap extending into the chuck and terminating below the bottom of the counterbore, and means for forcing the blank into the chuck onto the tap, said inclined ends of the faces providing a means for bringing the 45 faces of the blank into registration with the faces of the chuck prior to the time the blank engages the tap.
10. In a machine of the kind described, a 50 chuck for blanks, a holder in which the chuck is removably supported, means for rotating the holder, a tap stationarily held within the chuck, a hopper adjustable for various sizes of blanks, spring pressed blank receiving fingers adjacent the receiving end 55 of the chuck, means for removing blanks in consecutive order from the hopper to and between said receiving fingers, a gravity actuated plunger for forcing the blanks from said fingers into engagement with the tap in the chuck, said plunger being recessed at 60 the end to engage over the tap, and means for raising the plunger for successive operations, said means operating alternately relative to the means for positioning the blank between the fingers. 65
11. In a machine of the kind described, a 70 vertically positioned chuck for nut blanks, means for continuously rotating the chuck, a tap extending vertically into the chuck and stationarily held therewithin, a feed table, a hopper for blanks mounted thereon, a raceway for blanks extending from the bottom of the hopper to and over the receiving end of the chuck, a portion of the walls of the raceway above the chuck being swiveled to 75 move in a horizontal plane, a spring on each swiveled portion tending to force the walls together, means for consecutively removing blanks from the hopper and positioning them between said swiveled walls, a hollow 80 ended plunger actuated by gravity to force a blank from between said walls on to the tap in the chuck, and means for raising the plunger for successive operations.
12. In a machine of the kind described, a 85 hollow, rotatable chuck, a stationary tap within the chuck, means for consecutively positioning blanks at the receiving end of the chuck, and a plunger adapted to force the blank into the chuck onto the tap, the 90 plunger being recessed to receive the end of the tap.
13. In a machine of the kind described, a 95 hollow, rotatable chuck for blanks having a number of interior faces corresponding to the number of sides of the blank, and extending longitudinally therethrough parallel with the axis of the chuck, a stationary tap within the chuck, the chuck being counterbored at the blank receiving end and the tap 100 terminating adjacent the bottom of the counterbore, and automatic mechanism for delivering blanks consecutively into the chuck and onto the tap.
- In testimony whereof, I sign this specification in the presence of two witnesses.
- MAYHEW E. NOYES.
